UNITED STATES PATENT OFFICE.

HERBERT J. WOOD, OF MOUNT CLEMENS, MICHIGAN.

WASHSTAND.

1,168,450.

Specification of Letters Patent.

Patented Jan. 18, 1916.

Application filed May 22, 1915. Serial No. 29,729.

To all whom it may concern:

Be it known that I, HERBERT J. WOOD, a citizen of the United States, residing at Mount Clemens, in the county of Macomb and State of Michigan, have invented a new and useful Washstand, of which the following is a specification.

This invention relates to combined washstands and reservoirs, and its object is to 10 provide a device of this character which shall be pleasing in appearance, which can be thoroughly cleaned, and which shall not be liable to get out of order.

This invention consists, in combination 15 with a novel pedestal, of a bowl mounted on the upper end thereof, a reservoir surrounding the bowl and having a removable cover extending around the bowl, and novel means for permitting water to flow from 20 the reservoir to the bowl.

In the accompanying drawing, Figure 1 is a perspective view of the wash-stand with the front of the pedestal swung back to permit removal of the waste water receptacle. 25 Fig. 2 is a vertical central section taken at right angles to the view in Fig. 1.

Similar reference characters refer to like parts in both views.

The wash-stand shown in the drawing is 30 preferably made of cast-iron and sheet steel, properly enameled and consists of a top or cover, a reservoir, a bowl, a pedestal to support the bowl, a receptacle within the pedestal, means connecting the reservoir, bowl 35 and pedestal, and means controlling the flow of water from the reservoir to the bowl. The pedestal is formed of a base ring 1, preferably of cast-iron, a tapering body portion 2 mounted on the base, and a door 3 40 hinged to the part 2 to permit the receptacle or pail 4 for the waste water to be removed and replaced. The base 1 is preferably formed with a radial flange 5 on which the pail 4 may rest.

45 The reservoir is pressed or otherwise formed from sheet metal with a bottom 7 and walls 8. The top 9 has a down-turned outer flange 10 and an inner flange 12 which extends down into the bowl 13. It may be 50 connected to the rear wall of the reservoir by means of hinges 14, and be provided with an opening 15 to permit the operating button 16 of the valve to pass.

The bowl may be formed with a circumferential shoulder 17, properly drilled and threaded to receive screws 18 which pass

through holes in the outwardly turned flange 19 of the connector 20, through holes in the bottom 7 of the reservoir, and through holes in the packing ring 22, to hold these 60 various parts together. The cylindrical flange 23 on the connector 20 extends down into the upper end of the pedestal. The usual plug 24 may be secured to a staple 25 by means of a chain 26.

The device for controlling the flow of water to the bowl is very simple. A threaded boss 27 on the rounded bottom of the bowl 13 receives the nipple 28 which screws into the T 29. A plug 30 having a flange 32 65 presses the packing ring 33 against the bottom 7 and the T 29. This plug has holes 34 to permit the contents of the reservoir to flow into the T 29, and a central hole for the stem 35, to whose upper end the knob or 70 button 16 is secured. A disk 37 of any proper material is normally held against the bottom of the plug by the spring 38 and thus covers the lower ends of the holes 34. The lower end of the stem 35 is guided in 75 the hole 39 in the plug 40, which also supports the spring 33.

The details of construction of this device can all be changed without departing from the spirit of my invention as set forth in the 80 claims. Thus any proper means may be connected to the outlet opening of the bowl to carry off the waste water.

I claim:

1. In a wash-stand, the combination of a 90 pedestal having a flaring top ending in a radial flange, a reservoir having a flat bottom resting on said radial flange and provided with an opening substantially of the same diameter as the inner diameter of the 95 flange, a bowl substantially hemi-spherical extending into said opening in the bottom of the reservoir and having a flange resting on the edge of said bottom, said bowl having inlet and outlet openings, a connection 100 attached to the bottom of the reservoir and said inlet opening of the bowl, a valve to control the flow of water through said connection, and means to close the outlet opening.

2. In a wash-stand, the combination of a 105 pedestal and a bowl having an inlet opening in one side and a central outlet opening, a reservoir surrounding the bowl and having a flat bottom, a cover for the reservoir, 110 means to support the bowl and to form a watertight joint between the bowl and reser-

voir-bottom, a valve-body secured to the lower side of the reservoir-bottom, an operating stem for the valve extending upward through the cover and having a knob at its upper end, and means connecting the valve-body to the inlet opening in the bowl.

3. In a wash-stand, the combination of a bowl having an inlet opening, a reservoir surrounding the bowl and having a flat bottom, a cover for the reservoir, a T mounted just below the bottom, a pipe connecting one branch of the T to the inlet opening of the bowl, a plug screwing into a second branch of the T and through an opening in

the bottom of the reservoir and formed with 15 a flange to secure the T to said bottom and with a plurality of holes, at least one being adapted to permit water to flow into the T, a valve stem mounted in one of said holes and extending up above the cover, a valve 20 on the stem below the plug to close the holes therein, a spring to hold the valve against said plug and mounted within said T, and a plug screwed into the third branch of the T to support said spring. 25

In testimony whereof I have signed this specification.

HERBERT J. WOOD.
